UNITED STATES PATENT OFFICE.

J. ERWIN WAKEMAN AND ROBERT L. CROCKER, OF LOCKPORT, NEW YORK.

MACHINE FOR CONSTRUCTING BOXES.

SPECIFICATION forming part of Letters Patent No. 366,538, dated July 12, 1887.

Application filed September 9, 1886. Serial No. 213,083. (No model.)

To all whom it may concern:

Be it known that we, J. ERWIN WAKEMAN and ROBERT L. CROCKER, citizens of the United States, residing at Lockport, in the county of Niagara and State of New York, have invented a new and useful Machine for Making Boxes.

This invention pertains to certain new and useful improvements in machines for constructing boxes; and it consists in the detailed construction, combination, and arrangement of the parts, substantially as hereinafter described and claimed.

In the accompanying drawings, Figure 1 is a plan view of our invention. Fig. 2 is a longitudinal sectional view thereof, and Figs. 3 and 4 are details.

In carrying out our invention we secure to a board or table, A, an approximately V-shaped plate or iron, B, which has apertured projecting lugs b, whereby the same is secured by means of screws to the upper surface of said board or table, as shown in Fig. 1.

C is a plate disposed a short distance from the V-shaped plate or iron B, the vertical portion of said plate C being disposed against the opposite side walls of an aperture or opening, C, formed in the board or table A, and the horizontal projecting portions or lugs of said plate are apertured for the insertion of screws for retaining the same in position. This plate has oppositely-disposed apertured lugs b' b', between which is pivoted a cam-lever, D, the cam-like end of which being faced toward the V-shaped plate or iron B, the purpose of which will soon appear.

D' is a movable block having right-angularly disposed arms d d, the vertex of which is, when the block is in position, directly opposite the vertex of the plate B, as shown. This block has grooves in either side thereof for sliding on horizontally-projecting ways d' d' of the plate C, and within a central longitudinal aperture of this block is disposed a shouldered pin, d'', a spring, d'', also disposed therein, bearing against the shoulder on said pin. The outer end of this spring-pressed pin d'' bears against the forward wall of the aperture formed in the board or table A, and the normal action of the

spring on the pin is to cause the rear vertical end of the block D' to bear directly against the cam-like end of the lever D, the purpose of which will now appear.

This invention, it will be understood, is intended for putting together boxes having sides composed of single pieces of wood, the ends of which pieces are dovetailed for fitting in correspondingly-shaped mortises or sockets in the adjoining right-angularly disposed side of the box. This being the intention, the same is carried into effect by placing opposite corners of the box undergoing construction in the opposite vertexes of the plate or iron B and sliding block D', and by forcing down the lever D the cam-like end thereof will cause the sliding forward of the said block as against the action of the spring inclosed therein, and thus effectively secure the jointed ends of the box.

Having thus described our invention, what we claim, and desire to secure by Letters Patent, is—

1. The herein-described machine for constructing boxes, consisting of the board or table, the V-shaped plate or iron, the plate having projecting ways, the sliding block having the spring and shouldered pin inclosed therein, and the cam-lever arranged substantially as shown and described.

2. The combination, with the board or table and the V-shaped plate or iron secured thereto, of the sliding block having a central aperture and grooved in either side thereof, the guide-way-plate secured in an aperture of the said board or table, the headed pin inclosed in said aperture of the sliding block, the spring encompassing said pin, and the cam-lever, substantially as shown and described, the vertex of said V-shaped plate being opposed to that of the sliding block, as stated.

In witness whereof we affix our signatures in presence of two witnesses.

J. ERWIN WAKEMAN.
ROBERT L. CROCKER.
